(57) **CLAIM**

The ornamental design for a two way radio, as shown.

DESCRIPTION

FIG. 1 is a perspective view of the two way radio;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The broken line portions of the drawings form no part of the claimed design.
